UNITED STATES PATENT OFFICE.

ALBERT E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

TURN-SHOE MAKING.

1,362,627.

Specification of Letters Patent.

Patented Dec. 21, 1920.

No Drawing.

Application filed December 28, 1918. Serial No. 268,734.

To all whom it may concern:

Be it known that I, ALBERT E. JOHNSON, a citizen of the United States, residing at Beverly, in the county of Essex and State 5 of Massachusetts, have invented certain new and useful Improvements in Turn-Shoe Making; and I do hereby declare the following to be a full, clear, and exact description of the invention, such as will enable 10 others skilled in the art to which it appertains, to make and use the same.

This invention relates to improvements in turn shoe making and more particularly to a novel method of making turn soles which 15 adds quality to the finished shoe and perfects the shoemaking process.

In a turn shoe the feather surface of the sole which is exposed adjacent the upper is on the flesh side of the sole and consequently 20 it is rough in appearance requiring a finishing operation thereon. This finishing operation cannot be performed before turning the upper because after the sole and upper have been assembled the feather surface which finally is exposed is completely 25 covered by the lasted upper. Heretofore, therefore, the finishing operation has generally been performed as one of the final operations after turning. Shoe manufacturers have found that the upper is liable 30 to injury if an attempt is made to burnish the exposed feather or margin of the sole of the turned shoe and have been content to limit the finishing of the sole to an inking 35 operation only. Obviously, ink alone on the flesh side of the sole does not provide the finish that is desired.

The object of the present invention is to improve the method of making turn soles 40 in a manner that will produce a highly burnished margin without injury to the upper, thus enabling manufacturers who practise the methods to secure a finish on the exposed portion of the flesh side of the sole which will be pleasing in appearance 45 and harmonious with the finish of the remainder of the shoe.

By the present method it is proposed to ink the margin of the sole to its flesh side 50 and burnish the inked margin before the sole is incorporated in the shoe thus eliminating any possibility of injury to the

upper. Accordingly the sole is fitted in the usual way by channeling or channelling and shouldering, as may be desired for the 55 type of shoe being made, in any commercial turn sole channeler, such for example as is disclosed in Letters Patent of the United States to F. E. Bertrand No. 1,030,704, dated June 25, 1912. After channelling the sole is completed for incorporation in the shoe by inking, molding and burnishing its feather. It should be understood that the term "molding", as herein used, has reference to the breaking down 60 of the sole margin usually performed by a turn sole molding machine of the type disclosed in Letters Patent of the United States to William C. Meyer No. 1,110,637, dated September 15, 1914. 70

These steps are preferably although not necessarily performed in the order named. One method of proceeding is to first perform the usual sole molding operation and then ink and burnish the margin of the sole 75 in any convenient manner before assembling it with the upper. Those skilled in the art will recognize, however, that the sole molding operation must be performed in a machine having the molding roll which bears 80 on the feather provided with a smooth feather engaging face otherwise the succeeding steps of the present process can not be carried out successfully. Obviously, if the feather be roughened by engagement 85 with a feed wheel it cannot successfully be ironed smooth again and, furthermore, it will not take the ink perfectly. The best sole molding machine known to the inventor for use in practising the present method 90 is that disclosed in the A. E. Johnson application Ser. No. 258,758, renewed October 18, 1918 which resulted in Letters Patent of the United States No. 1,307,820, dated June 24, 1919, because in that machine the 95 sole is fed by its edge and the feather engaging face of the feather molding roll is smooth.

It will also be observed that the feather molding roll of said machine is of larger 100 diameter than the feed roll. Since these two rolls are driven from the same shaft the molding roll travels at a greater peripheral speed than the feed roll and consequently

where it engages the feather it acts as an ironing tool rapidly rubbing and burnishing the flesh side of the feather. Accordingly it is preferred to ink the margin of the sole 5 on its flesh side before performing the sole molding operation and then by using the machine of said Johnson patent the last two steps of the method, *i. e.* molding and burnishing the margin may successfully be performed simultaneously.

The machine of the Johnson patent lends itself readily to handling a turn sole the forepart of which has previously been shaped to the approximate contour of the last bottom, because of the size and arrangement of the molding and supporting rolls. A commercial machine which may be used for this forepart shaping operation is disclosed in Letters Patent of the United States 20 to E. Erickson No. 1,254,894, dated January 29, 1918. Accordingly when the margin molding and burnishing steps are performed by the turn sole molder of the Johnson patent the method may be enlarged by including therein the step of shaping the forepart 25 of the sole to the approximate contour of the last bottom, thus adding quality and accuracy to the shoemaking.

It will be observed that all of the steps of 30 the method described are performed on the sole prior to its incorporation in the shoe and that in the further process of making the shoe the burnished feather is covered and protected by the lasted upper. Consequently 35 when the shoe is turned the burnished margin is fresh and when the shoe is completed its entire appearance is pleasing because of the harmonious finish throughout. The practice of the method thus perfects the 40 methods heretofore employed whereby superior shoemaking is attained.

Having thus described the invention and the preferred manner of practising it, what is claimed as new, is:

1. The method of making turn soles which 45 includes the steps of inking the margin on the flesh side, and then simultaneously molding the margin and ironing the flesh side thereof to burnish the inked portion which is visible in the finished shoe.

2. The method of making turn soles which 50 includes the steps of channeling and shouldering the sole on its flesh side, inking the feather produced by the shoulder cut, and ironing the inked feather to burnish it before assembling the sole with the upper.

3. The method of making turn soles which 55 includes the steps of channeling, inking, molding and burnishing the margin of the sole, the last two operations being performed 60 simultaneously.

4. The method of making turn soles which 65 includes the steps of channeling, inking the margin on the flesh side, and then molding and ironing the inked margin.

5. The method of making turn soles which 70 includes the steps of channeling, shaping the forepart to approximate the contour of the last bottom, inking the margin on its flesh side, and finally molding and burnishing the margin of the shaped sole, all prior to incorporating the sole in the shoe.

6. That step in the method of making turn soles which consists in burnishing the flesh side of the margin of the sole prior to assembling with the upper.

7. That improvement in turn shoe making 75 which consists in ironing the inked feather of a turn sole to burnish said feather, prior to assembling the sole and upper.

ALBERT E. JOHNSON.
